UNITED STATES PATENT OFFICE.

WILLIAM H. UPTON, OF NEW YORK, N. Y.

PROTECTOR FOR VALVE-STEMS OF TIRES.

1,260,835.

Specification of Letters Patent. Patented Mar. 26, 1918

Application filed February 6, 1917. Serial No. 146,911.

To all whom it may concern:

Be it known that I, WILLIAM H. UPTON, a citizen of the United States, and resident of the borough of Manhattan, in the city and State of New York, have invented new and useful Improvements in Protectors for Valve-Stems of Tires, of which the following is a specification.

This invention relates to improvements in protectors for valve stems of tires, with the object in view of providing a device which will hold the valve securely in place and protect it from injury, and which may be applied and removed with a very slight manipulation.

Another object is to provide a device which has a closed end capable of being removed to give access to the valve cap, for inflating the tire, without going through the process of uncovering the entire valve stem, which projects above the felly.

A further object consists in providing certain improvements in the form, construction and arrangement of the several parts whereby the above named and other advantages may be effectively carried out.

A practical embodiment of my invention is represented in the accompanying drawings, in which—

Figure 1 represents a side elevation of my device applied to a valve stem, showing a portion of the felly in section.

Fig. 2 represents a longitudinal central section of the same.

Fig. 3 represents a similar view with certain of the parts released and the device ready to be removed from the stem.

Fig. 4 represents a horizontal section taken in the plane of the line IV—IV of Fig. 1.

Fig. 5 represents a horizontal section taken in the plane of the line V—V of Fig. 3.

Fig. 6 represents a side elevation of a modified form of device, and

Fig. 7 represents a longitudinal central section of the same.

The invention consists in general of a device designed for use in connection with a valve stem and the felly of the wheel and comprises a sleeve denoted by 1, which is of tubular form and has its inner end 2 provided with a plurality of longitudinal slots 3. This end 2 has an interiorly screw threaded portion 4 which is normally expanded and adapted to yield toward and away from

the valve stem 5. The yielding movement 55 of the end 2 is controlled by a member 6 which is provided with tongues 7 fitted to slide freely in the slots 3. The number 6 has formed thereon winged extensions 8 by which the member is readily manipulated. 60 The member 6 is also provided with a tubular shield 9 which covers the slots 3 and prevents dust and dirt from entering therethrough.

A washer 10 of leather or other suitable 65 material is held in a recess 11 in the member 6 and is arranged to be forced against the felly 12 around the valve stem 5.

To protect the outer end of the shield 9, the sleeve has formed thereon a housing 13, 70 in which the shield moves when the member 6 is manipulated.

In Figs. 1 to 3 inclusive, the sleeve is shown with a closed end 14 which has a screw threaded engagement therewith, as 75 shown at 15, and provided with ears 16, by which the cap may be manipulated.

In Figs. 6 and 7 the sleeve 1 has a closed end 17 formed integral therewith.

In using this device, the sleeve is passed 80 over the projecting valve stem 5 and the member 6 forced down upon the yielding portion of the sleeve, which causes the screw threaded portion to engage the threads on the valve stem 5. As the member 6 is rotated, it carries with it the sleeve which, through the tongue and slot engagement therewith, causes the washer 10 to be firmly 85 pressed against the felly 12, in which position the device is firmly locked to the felly 90 and stem. To release the device, the member 6 is rotated half a turn or more in a reverse direction from that previously described and the member slid upwardly on the sleeve 1, whereupon the threaded portion of the sleeve will spring outwardly, thus leaving the device free to be bodily removed.

In the form shown in Figs. 6 and 7, the device must be removed bodily to leave the 100 nipple in position to receive the pump for inflating the tire, while in Figs. 1, 2 and 3, the closed end 14 only is removed from the sleeve to expose the nipple to view.

It is evident that changes may be resorted to in the form, construction and arrangement of the several parts without departing from the spirit and scope of my in-

vention; hence I do not wish to limit myself strictly to the structure herein set forth, but

What I claim is:—

- 5 1. A protector for valves comprising a sleeve having a housing and a slotted end, said slotted end having normally expanded interior screw-threaded portions, means slidably interlocked with the slotted end for contracting said portions for bringing them into engagement with the valve stem, winged extensions for manipulating said means and a shield carried by said means and slidable in said housing for covering the slotted end of the sleeve.
- 10 2. A protector for valves comprising a sleeve having a capped end, a housing and a slotted end, said slotted end having normally expanded interior screw-threaded portions, means slidably interlocked with the slotted end for contracting said portions for bringing
- 15
- 20

ing them into engagement with the valve stem, winged extensions for manipulating said means, and a shield carried by said means and slidable in said housing for covering the slotted end of the sleeve. 25

3. A protector for valves comprising a sleeve having a removable cap, a housing and a slotted end said slotted end having normally expanded interior screw-threaded 30 portions, means slidably interlocked with the slotted end for contracting said portions for bringing them into engagement with the valve stem, winged extensions for manipulating said means and a shield carried by said means and slidable in said housing for covering the slotted end of the sleeve. 35

In testimony that I claim the foregoing as my invention, I have signed my name this 2nd day of February, 1917.

WILLIAM H. UPTON.
